United States Patent Office

Des. 182,761

Patented May 13, 1958

182,761

HAND DRYER

Warner A. Douglas, West Hempstead, N. Y.

Application August 2, 1957, Serial No. 47,199

Term of patent 14 years

(Cl. D4—3)

Fig. 1

Fig. 2

Fig. 2 is a side view of the hand dryer; and

Fig. 3 is a rear view of the hand dryer.

The undisclosed side of the hand dryer is the same in appearance as the side shown.

The dominant features of the design reside in the portions shown in full lines.

I claim:

The ornamental design for a hand dryer, as shown and described.
